CLAIM

The ornamental design for a laundry chemicals dispenser, as shown and described.

DESCRIPTION

FIG. 1 is a top, front perspective view for a laundry chemicals dispenser, showing our new design;

FIG. 2 is a bottom, front perspective view thereof;

FIG. 3 is an enlarged top view thereof;

FIG. 4 is an enlarged bottom view thereof;

FIG. 5 is a front view thereof;

FIG. 6 is a rear view thereof;

FIG. 7 is a right side view thereof; and,

FIG. 8 is a left side view thereof.

Portions of the laundry chemicals dispenser shown in broken lines form no part of the claimed design.

1 Claim, 7 Drawing Sheets(56)
